UNITED STATES PATENT OFFICE.

ALBERT B. WEGENER, OF CHICAGO, ILLINOIS.

HASP ATTACHMENT.

1,319,498.

Specification of Letters Patent.

Patented Oct. 21, 1919.

Application filed May 12, 1919. Serial No. 296,604.

To all whom it may concern:

Be it known that I, ALBERT B. WEGENER, a citizen of the United States, residing at Chicago, in the county of Cook and State 5 of Illinois, have invented certain new and useful Improvements in Hasp Attachments, of which the following is a specification.

This invention relates to means for attaching a hasp to the structure upon which 10 it is to be mounted, such, for instance, as the sliding door of a car, and it has for its object to provide means for firmly anchoring the mounting staple of the hasp.

Accordingly, the invention consists in 15 providing a plate through which the loop end of the staple may be introduced in position to hold the hasp with freedom of swinging movement, the staple having its inner ends so deflected that they become 20 firmly anchored in the plate and prevent the staple being drawn all the way through. The attaching plate is preferably secured by bolts or equivalent means which pass 25 through the plate and through the wall of the structure, and have nuts or equivalent means applied to their inner ends so that the staple cannot be released without first 30 gaining access to the interior of the structure.

30 A further object is to provide a construction of plate which will permit assembly of the hasp with the staple that is mounted in the manner described, and to this end, a further feature of the invention consists in 35 constructing the opening through the attaching plate so that the end of the hasp may be introduced thereinto, and permitted to protrude beyond the inner surface of the face a sufficient distance to permit the staple 40 to be threaded through the eye of the hasp, and then permit return of the hasp, accompanied by the loop end of the staple, to the front side of the plate.

The invention will be fully understood 45 upon reference to the accompanying drawings, in which—

Figure 1 is a front view of a hasp and its mounting embodying the several features of the present invention.

50 Fig. 2 is a top edge view of the same, the structure upon which the device is mounted being shown in section.

Fig. 3 is a perspective view illustrating 55 the relative positions of the parts at the time of assembly.

Fig. 4 is a section on the line 4—4 of Fig. 1.

Fig. 5 is a section on the line 5—5 of Fig. 1; and

Fig. 6 is a perspective view of the staple. 60 1 represents the staple which constitutes the attaching means for a hasp 2. According to the present invention, the staple 1 is mounted upon the structure, as, for instance, the door A of a freight car or other structure B, through means of an attaching plate 3 having a slot 3^a through which the loop end of the staple may be protruded in position to receive the eye 2^a of the hasp, said slot 3^a preferably corresponding in dimensions substantially to the superficial area of the loop end of the staple, and, therefore, firmly holding the same against distortion. In order to anchor the staple 1 in the plate 3, the staple has its inner ends deflected at such an angle to the sides of the loop as will limit the projection of the staple through the plate. These ends are preferably deflected from the plane of the loop and in opposite directions therefrom, as indicated in Fig. 6. Thus, the deflected ends of the staple provide a substantial base which, when firmly clamped between the attaching plate and the surface of the structure to which the hasp is to be applied, insure a rigid presentation of the staple in position perpendicular to the attaching plate, and resist any effort to distort the staple or draw it from its plate; stability in the plane of the staple being insured by the spacing 80 of the deflected ends 1^a from each other; and stability in the direction transverse to said plane being insured by the opposite projection of the ends. 85

To receive the anchoring ends 1^a of the staple and resist displacement thereof, and therefore prevent twisting, spreading, or other distortion of the staple, the under side of the attaching plate 3 has recesses 3^b, preferably trough-shaped, extending in 100 opposite directions from the respective ends of the slot 3^a, through which the loop of the staple is passed, and in depth corresponding substantially to the diameter of the anchoring ends, so that when the plate is 105 firmly held against the surface of the structure, the anchoring ends are firmly housed in sockets in the plate.

The plate 3 is attached through means of bolts 4, or equivalent attaching means, which 110

preferably have their external heads countersunk and square-seated in the plate 3 and spheroidal on the exterior so that they afford no gripping hold for tampering with the fixture; and these bolts pass through the plate, and through the wall of the structure, and receive nuts or equivalent securing means on their inner ends, so that removal of the plate and release of the staple can be accomplished only by first gaining access to the interior of the structure.

To permit assembly of the staple with the hasp, plate 3 is provided with an additional slot 3^c, as shown in Fig. 3, which 15 mits the end of the hasp 2 a sufficient distance to present its eye 2^a in convenient position for threading the staple 1 through the eye, said slot 3^c being located to intersect the slot 3^a so that after the staple is inserted 20 the hasp may be withdrawn along with the loop end of the staple to bring the parts into relation with the attaching plate which they retain when in use. Thus, the slots 3^a and 3^c combine to form an opening through 25 the plate of sufficient dimensions to pass both the eye end of the hasp and the loop end of the staple. The exact form of the opening is not the essence of this part of the invention, although substantial conformity 30 to the intersecting planes of the hasp and staple adds to the security of the device. Whatever the form of the opening may be, it is desirable to leave, opposite the inner end of each socket or recess 3^b, a wall 3^{bx} 35 that provides an abutment for the heel of the staple back of the anchoring end 1^a to resist violence that may be imposed upon the staple in a direction transverse to the plane of the loop.

40 The bolts 4^a adjacent the staple are preferably located at diagonally opposite points in the attaching plate, namely, in line with each socket 3^b. The attaching plate 3 is preferably provided with a rearward extension 3^d likewise secured to the structure, as, 45 for instance, through bolts 4^a, which naturally adds to the security of the closure, as it is obvious that with removal of the bolts 4^a adjacent the staple, and with the locking 50 end of the hasp still secured by seal or padlock, opening of the door would still be prevented since it is necessary to have the hasp free for manipulation through the slot 3^c before the staple can be disassembled from 55 its plate and the hasp released from the staple.

I claim:

1. In a hasp holder, an attaching plate, and a staple; said plate having an opening 60 passing the loop end of the staple therethrough, and said staple being constructed at its inner end to arrest its passage through said opening.
2. The combination of a hasp, a staple 65 engaging said hasp, and a plate for attach-

ing said staple; said plate having an opening passing the loop end of the staple therethrough, and said staple being constructed at its inner end to arrest its passage through said opening.

3. In a hasp holder, a staple, and a plate for attaching the staple having an opening corresponding substantially to the superficial area of the loop end of the staple; an inner end of the staple being deflected from the plane of the loop and thereby limiting the passage of the staple through the opening of the plate.

4. In a hasp holder, a staple, and a plate for attaching the staple having an opening 80 corresponding substantially to the superficial area of the loop end of the staple; the inner ends of the staple being deflected in opposite directions from the plane of the loop of the staple.

5. In a hasp holder, a staple, and a plate for attaching said staple; said plate having a slot admitting the loop of the staple in position to receive the hasp; said staple having its ends deflected from the plane of the loop to arrest passage of the staple through the plate; and said plate having upon its under side seats for the deflected ends of the staple.

6. A hasp holder comprising a staple, and a plate for attaching the staple; the staple having its inner ends deflected perpendicularly to the plane of the loop of the staple, and said plate having a slot admitting the loop of the staple in position to receive the hasp, and provided with sockets on its under side extending from said slot in position to receive the deflected ends of the staple to resist displacement of said ends by distortion of the loop.

7. A hasp holder comprising a staple and a plate for attaching the staple; the staple having its inner ends deflected perpendicularly to the plane of the loop of the staple; said plate having a slot admitting the loop of the staple in position to receive the hasp, and provided with sockets on its under side extending from said slot in position to receive the deflected ends of the staple to resist displacement of said ends by distortion 115 of the loop; and said slot having walls presented to the inner ends of said sockets and opposing withdrawal of the deflected ends from the sockets.

8. In a hasp holder, a staple having its 120 ends positioned perpendicularly to and in opposite directions from the plane of its loop and providing a base which resists tipping of the staple in the plane of its loop or transversely thereto, and a plate fitted over said base and adapted to confine said base upon the structure upon which the hasp is to be mounted.

9. A hasp holder comprising a staple, and a plate having an opening adapted to pass 130

the end of the hasp and the loop of the staple assembled therewith; said staple being constructed to limit the distance to which it follows the hasp through the plate.

5 10. A hasp holder comprising a staple adapted to be received by the eye of a hasp, and a plate having two intersecting slots respectively positioned to receive the end of the hasp and the loop of the staple when 10 engaged with the hasp; said staple having its inner end constructed to limit its passage through the plate.

11. In combination with a hasp having an eye at one end, a staple having a loop engaged with said eye, a plate having a slot adapted to receive the end of the hasp, and an intersecting slot adapted to receive the 15 loop of the staple; the respective inner ends

of the staple being deflected in opposite directions from the ends of the staple-receiving slot and bearing beneath the plate to limit the projection of the loop of the staple through the plate.

12. The combination of a hasp, a staple having its loop engaged in said hasp and having a base enlarged beyond the plane of its loop, a plate having a slot receiving said loop and fitting over said base, and attaching means passing through the plate on opposite sides of the staple and having securing means adapted to hold their inner ends on the opposite side of a structure to which the hasp is applied.

Signed at Chicago, Illinois, this third day of May, 1919.

ALBERT B. WEGENER.
